SUPPRESSION OF METAL CATALYSIS

Joseph A. Chencik, Chicago, Ill., assignor to
Universal Oil Products Company, Chicago, Ill.,
a corporation of Delaware

No Drawing. Application April 6, 1940,
Serial No. 328,523

23 Claims. (Cl. 44—73)

This invention relates to a method for suppressing deterioration of olefin-containing hydrocarbon distillates such as results from the catalytic effect of metal compounds on oxidation reactions involving unsaturated hydrocarbons and resulting in the formation of gum.

The use of gasoline gum inhibitors to prevent or minimize oxidation reactions resulting in the formation of objectionable peroxides, gums and other deleterious oxidation products has been practiced. They are particularly useful in cracked, reformed and polymer gasolines which contain relatively high concentrations of mono-olefins and somewhat smaller concentrations of other unsaturated hydrocarbons such as diolefins.

The function of inhibitors is primarily to minimize or prevent such oxidation reactions and thus keep the motor fuel in satisfactory condition for use in internal combustion engines. They tend to prevent losses in antiknock value which accompanies oxidation of this type of gasoline. Among the materials which have been used are various phenolic and amino compounds as well as fractions of wood tar oil particularly from hardwood tars boiling in the range of about 240—280° C., etc., which are usually added to the gasoline in concentrations of approximately 0.001—0.1%, depending upon the effectiveness of the particular compound used and the gasoline to which it is added.

Although inhibitors are used in both treated and untreated gasolines, it is with the latter type that they find the greatest application. Treated gasolines are those which have been subjected to chemical refining processes such as sulfuric acid, fuller's earth, and the like, either with or without a sweetening treatment following. Untreated gasolines are those which have received no refinement beyond possibly caustic washing and/or sweetening. The former type of gasoline is usually relatively stable and requires little or no added inhibitor, although the use of inhibitors has been practiced to supplement other refining methods. In the case of untreated gasolines, on the other hand, many of them are unstable and require the protection afforded by inhibitors to prevent undue deterioration during the time they are in storage.

Practically all gasolines require some form of sweetening treatment in order to improve the odor thereof and produce a product having a negative doctor test. The sodium plumbite or doctor process, as well as the hypochlorite sweetening process, have been used in the past with considerable success. During recent years, the

so-called copper sweetening process has been developed in which gasoline is contacted with a copper-containing reagent. As a result of the presence of relatively minor amounts of impurities in such gasolines, the sweetened gasoline usually contains relatively small amounts of copper compounds which have a catalytic effect on oxidation reactions which may result when the gasoline comes in contact with air. Various methods have been developed for removing such copper compounds including treatment with alkali or alkaline earth metal sulfides, and heavy metal sulfides such as zinc sulfide and the like. In some instances, however, these reagents may not be completely effective in removing the copper from the gasoline and as a consequence the gasoline may have a reduced stability and susceptibility to added gasoline gum inhibitors. Moreover, gasolines come in contact with various metals in the course of refining, storing and shipping operations, and this may result in the gasoline containing minute amounts of such metals as copper, iron, cobalt, nickel and the like which are oxidation catalysts. It is with a method of preventing depreciation due to the presence of such catalysts that this invention is concerned.

In one specific embodiment the present invention comprises a method for suppressing the catalytic action of metal compounds which may be contained in hydrocarbon distillates such as gasolines, and which tend to promote the formation of gum therein by adding to said gasoline approximately 0.0001—0.01% of a condensation product of an orthohydroxy aromatic aldehyde and a primary alkyl amine either with or without a gasoline gum inhibitor.

Compounds of this type may be represented by the general formula:

48 or

wherein R is a substituent group such as hydrogen, alkyl, aryl, hydroxyl, halogen, nitro, alkoxy, aryloxy or amino group, and R' is an alkyl group. Typical examples of this type of compound are orthohydroxy benzaldehyde

utylimine, orthohydroxy benzaldehyde ethylimine, orthohydroxy benzaldehyde octyl-imine, -hydroxy-1-naphthaldehyde butylimine.

The compounds of this invention, which are hereinafter termed suppressers, are not necessarily exactly equivalent. Furthermore they possess varying degrees of solubility in hydrocarbon distillate which may influence the effectiveness if any given stock. The proper choice of a suppresser for any particular oil will depend upon these factors and is, in the end, a matter of test.

In some cases the compounds may be used in the gasoline without added gum inhibitors. This is particularly true when used in connection with straight-run distillates or cracked gasolines which have been refined to an adequate degree of stability such as by acid-treatment or other suitable methods. However, these compounds are not of themselves gasoline gum inhibitors except to a minor extent, so that they do not result in a gasoline of improved stability except when metal compounds are present therein.

However, the usual method of application is to add both the suppresser and the gasoline gum inhibitor simultaneously. The resulting induction period is usually the same or slightly increased over that obtainable with the inhibitor alone in a gasoline free of metal compounds. The suppresser may be dissolved in the gasoline gum inhibitor. As a rule, smaller amounts of the suppresser are required than of the gum inhibitor, so that a relatively minor amount of the suppresser may be added to the inhibitor, say for example, less than 50% of the total mixture.

The following example is given to illustrate the usefulness of the invention, but should not be construed as limiting it to the compounds shown therein.

A cracked Pennsylvania gasoline which had been copper-sweetened was found to contain 1 mg. of copper/liter of gasoline. The induction period by the oxygen bomb method was 40 minutes. Upon the addition of N-butyl aminophenol, the induction period was increased to 85 minutes. Representative compounds of this invention were added to the inhibited gasoline with the following results. When adding 0.01% of orthohydroxy benzaldehyde ethylimine, the induction period was 270 minutes, with orthohydroxy benzaldehyde butylimine the induction period was 220 minutes, with orthohydroxy benzaldehyde octyl-imine the induction period was 170 minutes, and the 2-hydroxy-1-naphthaldehyde butylimine the induction period was 255 minutes.

I claim as my invention:

1. A process for suppressing the catalytic effect of metal compounds on hydrocarbon distillate which comprises adding to said distillate a relatively minor portion of a metal-free condensation product of an orthohydroxy aromatic aldehyde and a primary alkane mono-amine.

2. A process for suppressing the catalytic effect of metal compounds on gum formation in olefin-containing hydrocarbon distillate which comprises adding to said distillate a relatively minor portion of a metal-free condensation product of an orthohydroxy aromatic aldehyde and a primary alkane mono-amine.

3. A process for suppressing the catalytic effect of metal compounds on gum formation in cracked gasoline which comprises adding to said gasoline a relatively minor portion of a metal-

free condensation product of an orthohydroxy benzaldehyde and a primary alkane mono-amine.

4. A process for suppressing the catalytic effect of metal compounds on cracked gasoline which comprises adding to said gasoline a gum inhibitor and a metal-free condensation product of an orthohydroxy aromatic aldehyde and a primary alkane mono-amine.

5. A process for suppressing the catalytic effect of metal compounds on cracked gasoline which comprises adding thereto a metal-free condensation product of an orthohydroxy mono-nuclear aromatic aldehyde and a primary alkane mono-amine.

10 6. A process for suppressing the catalytic effect of metal compounds on cracked gasoline which comprises adding thereto a metal-free condensation product of an orthohydroxy polynuclear aromatic aldehyde and a primary alkane mono-amine.

15 7. A process for suppressing the catalytic effect of metal compounds on cracked gasoline which comprises adding thereto an N-substituted alkyl aminophenol and a metal-free condensation product of an orthohydroxy aromatic aldehyde with a primary alkane mono-amine.

20 8. A process for suppressing the catalytic effect of metal compounds on cracked gasoline which comprises adding thereto a wood tar distillate 30 gasoline gum inhibitor boiling within the range of approximately 240-280° C. and a metal-free condensation product of an orthohydroxy aromatic aldehyde with a primary alkane mono-amine.

25 9. A process for suppressing the catalytic effect of metal compounds on hydrocarbon distillate which comprises adding thereto 2-hydroxy-1-naphthaldehyde butylimine.

30 10. A process for suppressing the catalytic effect of metal compounds on cracked gasoline which comprises adding thereto a metal-free condensation product of an orthohydroxy benzaldehyde and a primary alkane mono-amine in an amount within the limits of approximately 45 0.0001-0.01%.

11. A process for suppressing the catalytic effect of metal compounds on olefin-containing hydrocarbon distillate which comprises adding thereto a metal-free compound whose general 50 formula includes the structure:

55 wherein R is an alkane group.

12. A process for suppressing the catalytic effect of metal compounds on olefin-containing hydrocarbon distillate which comprises adding thereto a metal-free compound whose general formula includes the structure:

65 wherein R is an alkane group.

13. An inhibitor of gum formation in cracked gasoline containing metal compounds comprising essentially a mixture of a gasoline gum inhibitor with a metal-free condensation product of an orthohydroxy aromatic aldehyde and a primary alkane mono-amine.

70 14. An inhibitor for cracked gasoline contain-

ing metal compounds comprising essentially a mixture of a gum inhibitor with a metal-free condensation product of an orthohydroxy mono-nuclear aromatic aldehyde with a primary alkane mono-amine.

15. An inhibitor for cracked gasoline containing metal compounds comprising essentially a mixture of a gasoline gum inhibitor with a metal-free condensation product of an orthohydroxy poly-nuclear aromatic aldehyde and a primary alkane mono-amine.

16. An inhibitor for cracked gasoline containing metal compounds comprising essentially a mixture of an N-substituted alkyl aminophenol, with a metal-free condensation product of an orthohydroxy aromatic aldehyde with a primary alkane mono-amine.

17. An inhibitor for cracked gasoline containing metal compounds which comprises essentially a mixture of a wood tar distillate gum inhibitor boiling in the range of approximately 240-280° C. with a metal-free condensation product of an orthohydroxy aromatic aldehyde and a primary alkane mono-amine.

18. Method of stabilizing gasoline containing traces of metallic compounds catalytically active to accelerate oxidation comprising adding there-to a small quantity of suppresser compound having the formula

where R is alkyl.

19. Method of stabilizing gasoline containing traces of metallic compounds catalytically active to accelerate oxidation comprising adding there-

5 to a small amount of a hydroxy aromatic compound containing the radical $\text{CH}=\text{NR}$ directly attached to the aromatic ring and in which R is an alkyl group, the hydroxy group of the aromatic nucleus being in the ortho position with respect to said radical.

10 20. Motor fuel comprising olefinic gasoline containing metallic compounds catalytically active to accelerate oxidation, and a relatively small amount of a metal-free hydroxy aromatic compound containing the radical $\text{CH}=\text{NR}$ directly attached to the aromatic ring and in which R is an alkyl group, the hydroxy group of the aromatic nucleus being in the ortho position with respect to said radical.

15 21. Motor fuel comprising olefinic gasoline containing metallic compounds catalytically active to accelerate oxidation, and a relatively small amount of a metal-free condensation product of 20 an orthohydroxy aromatic aldehyde and a primary alkane mono-amine.

25 22. Motor fuel comprising olefinic gasoline containing metallic compounds catalytically active to accelerate oxidation and relatively small amounts of a gum inhibitor and a metal-free hydroxy aromatic compound containing the radical $\text{CH}=\text{NR}$ directly attached to the aromatic ring and in which R is an alkyl group, the hydroxy group of the aromatic nucleus being in the 30 ortho position with respect to said radical.

23. Motor fuel comprising olefinic gasoline containing metallic compounds catalytically active to accelerate oxidation, and relatively small amounts of a gum inhibitor and a metal-free condensation product of a orthohydroxy aromatic aldehyde and a primary alkane mono-amine.

JOSEPH A. CHENICEK.
